UNITED STATES PATENT OFFICE.

FREDERICK YEISER, OF DANVILLE, KENTUCKY, ASSIGNOR OF ONE-HALF
HIS RIGHT TO DANIEL H. YEISER, OF SAME PLACE.

IMPROVEMENT IN CAR-COUPINGS.

Specification forming part of Letters Patent No. 147,734, dated February 17, 1874; application filed
June 24, 1873.

To all whom it may concern:

Be it known that I, FRED. YEISER, of Danville, in the county of Boyle and in the State of Kentucky, have invented certain new and useful Improvements in Car-Coupling; and do hereby declare that the following is a full, clear, and exact description thereof, reference being had to the accompanying drawings, and to the letters of reference marked thereon, making a part of this specification.

The nature of my invention consists in combining, with an ordinary pin and link coupling, a swinging bar under each draw-head, weighted at its inner end, and provided with an upward-projecting flange or lip at the outer end, for the purpose of supporting the link and guiding the same while coupling the cars, as will be hereinafter more fully set forth.

In order to enable others skilled in the art to which my invention appertains to make and use the same, I will now proceed to describe its construction and operation, referring to the annexed drawing, in which—

Figure 1 is a side view; Fig. 2, a longitudinal vertical section of my improved car-coupling; and Fig. 3 is a longitudinal section, showing my invention in the act of coupling.

A A represent two ordinary draw-heads, with coupling-pins B B and coupling-link C. Under each draw-head swings a board or bar, D, by means of arms a a, which are pivoted to said bar, and to the draw-head A. On the rear end of the bar D is secured a weight, E, and at the front or outer end is formed a flange or lip, b, which projects upward. In the outer end of the bar D, immediately in rear of the

flange or lip b, is a hole or aperture, through which the coupling-pin B passes when the cars are coupled. When the pin is drawn up out of the hole in the bar D, the weight E will throw the outer end of said bar forward and upward, so that the flange or lip b will extend up in front of the end of the draw-head, and thus support and hold the link in a proper horizontal position to enter the opposite draw-head. The pin in this draw-head being placed in an inclined position in the pin-hole, in the top of the draw-head, when the cars are brought together to be coupled, the concussion will jar this pin so that it will fall down vertically to its proper position. At the same time the front ends of the bars D D strike each other, and the rear sides of the lips being curved, they both slide back from under the lower edges of the draw-bars, and the pins fall down into and through the holes in the bars, as shown in the drawing.

Having thus fully described my invention, what I claim as new, and desire to secure by Letters Patent, is—

In combination with an ordinary pin and link coupling, the swinging bars D, having weights E at their inner ends, and flanges or lips b at their outer ends, substantially as and for the purposes herein set forth.

In testimony that I claim the foregoing, I have hereunto set my hand this 26th day of May, 1873.

FREDERICK YEISER.
